UNITED STATES PATENT OFFICE.

HERMANUS GERARDUS MONKHORST, OF DELFT, NETHERLANDS.

PACKING-MACHINE.

1,324,166.

Specification of Letters Patent.

Patented Dec. 9, 1919.

Application filed July 25, 1919. Serial No. 313,407.

To all whom it may concern:

Be it known that I, HERMANUS GERARDUS MONKHORST, a subject of the Queen of the Netherlands, residing at Delft, Netherlands, 5 have invented certain new and useful Improvements in Packing-Machines, of which the following is a specification.

My present invention relates to machines for packing fatty, greasy, highly hygroscopic or similar substances such as yeast, butter, margarine, etc., substantially in the 10 form of rectangular prismatic or parallelepipedic blocks of predetermined size.

The primary object of my invention is to 15 prevent the material to be packed from adhering to some part of the machine which, especially in the case of yeast, might give rise to deterioration and infection of the material, and to interference with the 20 proper working of the apparatus. With this and other objects in view my novel construction comprises a plurality of mechanisms regularly spaced apart about an intermittently rotary shaft, each mechanism being adapted to hold a block with a sheet of 25 paper or the like partly wrapped around it and convey same to members for successively folding said sheet all around the block, and formed as grippers adapted to reciprocate 30 radially with respect to the shaft so as to be adapted to pick up a block suitably supported outside the machine.

An embodiment of my invention is illustrated in the annexed drawing in which:

35 Fig. 1 is a somewhat diagrammatic elevational view of the machine,

Fig. 2 is an elevation partly in section along Y—Y in Fig. 3 of part of the machine, including a gripper;

40 Fig. 3 is a sectional view along X—X in Fig. 2;

Fig. 4 is a sectional view along Z—Z in Fig. 3;

Fig. 5 is an elevation partly in section of 45 a paper clip adapted for use in connection with my new apparatus.

The substance to be packed must be supposed to be periodically delivered in the 50 form of rectangular prismatic or parallelepipedic blocks on to a band conveyer 1 having intermittent motion in a direction at right angles to the plane of the drawing. Said conveyer moves the blocks vertically below a four-armed spider 2 adapted to intermit-

tently revolve about a horizontal shaft 3 55 through angular distances of 90° each, it being understood that the conveyer 1 should be properly timed with respect to the spider 2.

Each arm of the spider 2 comprises a cylinder 4 (see Fig. 2) whose piston 5 carries a gripper, a passage 6 being provided for the admission of compressed air on the inner side of the piston. At either side of the cylinder the spider is provided with a guide 60 bar 7 insuring rectilinear motion to the gripper during its radial displacements.

Each gripper (see Figs. 3 and 4) comprises a rectangular plate 9 connected with the piston rod 8 and having at opposite 70 sides recesses for receiving the guide-bars 7. At the same sides of said plate eyes 10 are provided for receiving bolts 11 to which pressure plates 12 are hinged. The said pressure plates are loaded by springs 13 75 bearing with one end against the inner side of the plates 12 and with their other ends against a bracket 14 secured to the plate 9, in such a manner that those portions of the plates 12 that are located at the outside of 80 the bolts 11 are forced to one another. The springs 13 are thrown around bolts 15 passing through holes in the bracket 14 and engaged by coiled springs 16 connected at 85 17 with the spider 2.

At the side of each gripper the spider 2 has secured to it a paper clip 18. Said clip comprises two jaws 20, 21 of which the jaw 20 may be fixed in position on a bolt 19 (see Fig. 5), a spring 22 tending to keep the jaws 90 closed. Secured to the jaw 21 is an arm 23 adapted to coöperate with one of two stop members 24, 25 adjustably mounted on the frame in such a manner that when passing along said members the jaw 21 is forced 95 away from the jaw 20 against the action of spring 22.

In the close proximity of the stop member 24 opens a chute 26 through which the packing paper 27 from a suitably supported 100 roller is periodically fed to the clip 18, knives 28 being provided to cut the paper into sheets of the required size. The said paper feeding device is so constructed that the moment when the jaws 20, 21 are moved 105 from one another by the engagement of the arm 23 with the member 24 a sheet of paper falls out of the chute 26; but the details of

construction of said mechanism are of no importance as far as the present invention is concerned.

The further construction of my packing machine will be described hereinafter when explaining its operation.

The spider 2 after having rotated through an angular distance of 90° assumes a position wherein one of the grippers is vertically 10 above the conveyer 1 which at such moment is stationary, the clip 18 coöperates with the stop member 24 in such a manner that the jaws 20, 21 are kept at a suitable distance from one another. In this moment the 15 knife 28 cuts a sheet of suitable size from the packing paper 27 whereby said sheet enters the clip 18. As soon as the spider 2 now begins to rotate in the direction of the arrow A the arm 23 disengages the stop 20 member 24 whereby the jaws 20, 21 grip the sheet of paper between them and said sheet is obliged to follow the rotary motion of the spider. In the meantime one of the blocks 25 (a) on the conveyer 1 has moved into position vertically below the spider 2 so that if the spider has completed its rotation through 90° and come to rest the gripper located at the left hand side of the said clip 18 assumes a position vertically above the said block. 30 The sheet of paper gripped between the jaws 20, 21 of said clip 18 now evidently rests on the top of block a with two flaps depending at either side of the block, it being understood that at such moment the sheet of paper 35 has been released by the clip 18 owing to the stop member 25 having forced the jaws 20, 21 from one another. At this moment compressed air is admitted on the inner face of the piston of the said gripper by which the 40 piston 5 is radially forced outward and the pressure plates 12 moved downward closely along the sides of the block a, thereby folding the depending flaps smoothly over these sides. The springs 13 are adapted to press 45 the plates 12 with suitable force against the sides of the block so that if the admission of compressed air is interrupted and the air behind the piston discharged the block a is lifted by the action of the springs 16 and 50 assumes the position a¹.

It is clear that the gripper does not contact directly with the block to be packed, as a sheet of packing paper is placed between the block and the gripper from the outset. 55 During the following rotation of the spider 2 through 90° the block a is always gripped in an invariable position relative to the said gripper, so that there is no objection to printing the packing paper immediately before the same is folded around the block provided the ink be printed on that face of the paper which when wrapped around the block is outside, and on that part of the sheet which is intended to cover the top face of

the block. It will be understood that in this case the ink is protected during a sufficiently long time from contact with any part moving with respect to the block, and that it may have dried hard at the end of the operation.

After the spider 2 has rotated through 90° and come to rest with the block a in the position indicated by a², a plate 29 actuated by compressed air moves upwardly, thereby folding the lower depending flap of the packing paper over that side of the block which on the conveyer 1 formed the bottom. The said plate 29 is preferably provided with a plurality of very narrow outlets through which compressed air is discharged, by 80 which the said flap of the packing paper is kept in contact with the block until the next rotation through 90° of the spider has commenced. During this rotation the block moves without any appreciable friction 85 along a stationary cylindrical plate 30 which is concentric with the shaft 3 and located at such a distance from said shaft as to cause the upper depending flap of the packing paper to be folded over the first 90 named flap, so that when the block arrives in the position a³ the same is covered by the packing paper both at bottom and top and at its two sides.

When the spider 2 is stationary with the block in the position a³, two folding plates 31, 32 are successively moved in a horizontal, and a vertical direction respectively, closely along the front and the rear face of the block, by which the paper is folded inward 100 over the said faces along the right hand edge and the top edge.

During the next revolution through 90° the block is moved closely along two stationary plates 33, 34 having for their purpose to fold the paper inwardly over front and rear faces along the remaining edges so that the block when arriving in its position a⁴ is entirely packed, after which it is forced 110 out of the machine by means of a pressing cylinder 35.

The drawing does not show in detail the manner in which the spider 2 is intermittently revolved and the compressed air actuates the various pistons at the proper times, 115 it being understood that these means do not form part of the invention. It may be stated, however, that in the example illustrated the distribution of the compressed air is effected by a plurality of valve chests 36, cams 37, and the necessary piping, the said cams being driven by a shaft 38 which also drives the shaft 3 of the spider.

The clips 18 may be provided with electrical contacts 39, 40 (see Fig. 5) so arranged 125 that when the jaws 20, 21 are forced into engagement by the spring 22 an electrical circuit is closed whenever a sheet of paper

should have failed to fall between said jaws. The closure of said circuit energizes an electromagnet adapted to stop the machine.

What I claim as my invention is:

- 5 1. A packing machine comprising an intermittently rotating shaft a plurality of grippers spaced apart around said shaft, means for conveying a block of the material to be packed to a position adjacent one of
10 the grippers, and means for covering said

block with paper, said gripper adapted to reciprocate radially and pick up the block covered by the sheet of packing paper.

2. A packing machine as claimed in claim 1, in which the gripper comprises a central plate and two sides plates pivoted thereto and having their working faces yieldingly pressed toward one another. 15

In testimony whereof I affix my signature.

HERMANUS GERARDUS MONKHORST.
